UNITED STATES PATENT OFFICE.

FREDERICK CRAIB, OF MARTINEZ, CALIFORNIA.

DESIGN FOR A BRACKET ARM.

Application filed May 22, 1922. Serial No. 2,343. Term of patent 3½ years.

To all whom it may concern:

Be it known that I, FREDERICK CRAIB, a citizen of the United States, residing in the town of Martinez, county of Contra Costa, and State of California, have invented a new, original, and ornamental Design for a Bracket Arm, of which the following is a specification, reference being had to the accompanying drawings, forming part thereof.

Fig. 1 is a front elevation of the bracket arm, and Fig. 2 is a side elevation, showing my new design.

I claim:

The ornamental design for a bracket arm, as shown.

FREDERICK CRAIB.
